UNITED STATES PATENT OFFICE.

GEORGE R. PAULUS, OF CANTON, OHIO, ASSIGNOR TO THE UNITED ELECTRIC COMPANY, OF CANTON, OHIO, A CORPORATION OF OHIO.

VACUUM-CLEANER BRUSH.

1,393,695.

Specification of Letters Patent. Patented Oct. 11, 1921.

Application filed September 12, 1918. Serial No. 253,698.

To all whom it may concern:

Be it known that I, GEORGE R. PAULUS, a citizen of the United States, residing at Canton, in the county of Stark and State of Ohio, have invented certain new and useful Improvements in Vacuum-Cleaner Brushes, of which the following is a specification.

The invention relates to the suction shoe or nozzle chamber of a vacuum cleaner, and 10 the object of the improvement is to provide a rotary brush for taking up threads, ravelings, lint and other long, light or fluffy materials, and to mount and operate the same so as to efficiently perform its functions and 15 to be readily and easily removed and replaced for cleaning, repairing or renewing.

In the use of vacuum cleaners, it is difficult to take up threads, long ravelings, and 20 lint from the nap of body brussels or velvety rugs and carpets, for the reason that the strings, ravelings and lint are so held by the fiber of the nap that they cannot be removed by the suction of the machine.

When a cleaning brush is geared to and 25 driven by a rotary fan or other vacuum producing mechanism, it operates with a greater speed and more positive action than is necessary or desirable, and it is also driven solely in one direction; which excessive 30 speed and positive action are injurious to the floor coverings.

The present improvement overcomes 35 these difficulties by utilizing one of the casters of the machine as a traction wheel from which the brush is driven by a short resilient belt riding in a peripheral groove in the 40 caster; and for ready and easy removal and replacement, the axial spindle of the brush is detachably mounted between an engaging bearing at one end and a spring bearing at the other end.

A preferred embodiment of the invention is illustrated in the accompanying drawings forming part hereof, in which—

45 Figure 1 is a perspective view of the under side of a suction shoe showing the improved brush mounted therein;

Fig. 2, a longitudinal section showing the method of mounting the brush stem between 50 its bearings; and

Fig. 3, a fragmentary perspective view showing the method of engaging one end of the stem with its bearing.

Similar numerals refer to similar parts 55 throughout the drawings.

The forward and rear walls 1 and 1^a of the suction shoe are usually connected or formed on the lower forward side of the fan case 2 of a portable electric machine, and the end walls 3 and 3^a of the shoe are preferably extended rearward from the body of the shoe and are joined by rear walls 4 and 4^a with adjacent side walls 5 and 5^a to form bearings and housings for the casters 6 and 6^a located at the rear of the ends of the shoe. The wall 5 is preferably extended forward to constitute one end wall of the suction chamber 7; and the wall 5^a preferably terminates at the rear wall 1^a of the shoe, so that the wall 3^a forms the other end of the suction chamber. 70

The rotary tubular bearing 8 for one end of the tubular spindle 9 of the brush 10, is swiveled at its outer end upon the journal 11 formed by the stem of the screw 12 secured in the end wall 3 of the shoe. This 75 bearing extends through the aperture 13 in the wall 5 and is provided in its inner end with the transverse pin 14 adapted to engage with the notches 15 in the end of the brush spindle 9, which in turn is adapted 80 to be entered neatly into the end of the tubular bearing 8, as shown in Fig. 2.

The pivotal bearing 16 for the other end of the tubular spindle 9 of the brush 10 is slidably swiveled by its cylindric head 17 85 in the stationary tubular bearing 18 secured as by screwing in the other end wall 3^a of the shoe. The compression spring 19 is provided in the tubular bearing and normally acts against the head 17 to protrude the pivotal bearing 16 from the stationary bearing 18 far enough to enter the one end of the tubular spindle 9 of the brush when the other end thereof is engaged with the rotary bearing 8, as described. 95

By this construction and arrangement, when it is desired to remove or replace the brush from its bearings, it is only necessary to move the tubular spindle of the brush longitudinally so as to slide the pivotal bearing 16 endwise in the stationary bearing 18, against the action of the spring 19, far enough to disengage or engage the other end of the tubular spindle 9 with the rotary bearing 8, as the case may be; and when the 100 brush spindle is engaged therewith, it is evident that a turning of the rotary bearing will revolve the brush upon the pivotal bearing 16 at the other end of the stem. 105

The parts are so proportioned and ar- 110

ranged that there is a slight or free end clearance between the brush spindle 9 and the several bearings, thus preventing any end pressure or friction from retarding the 5 rotation of the brush spindle.

A portion of the rotary bearing 8 opposite the caster 6 is diagonally serrated cross-wise, so as to provide an adhering surface for the resilient cable or belt 20; and the 10 periphery of the caster 6 is provided with the annular groove 21 in which said belt is adapted to operate for rotating the brush, without coming in contact with the floor or its coverings.

15 By this construction and arrangement, it is obvious that as the cleaning shoe of the machine is moved forward and rearward over the objective surface, the caster 6 serves as a traction wheel to rotate the 20 cleaning brush first one way and then the other; and that while the driving belt 20 normally drives the brush in one direction or another, it may yet slide or slip around the traction caster 6 to a sufficient extent to 25 compensate for any stoppage there may be in the rotation of the brush, without inter-

fering in any way with the action of the vacuum creating mechanism. It is also evident that by using a resilient material for the belt 20, its efficiency for driving the 30 brush will be increased, although it is not intended to limit the scope of the invention to the use of a resilient belt.

I claim:

1. In a vacuum cleaner suction shoe, screw 35 plugs in the ends of the shoe, swiveled bearings carried by the plugs, one of the bearings having spring cushioned endwise movement, and a brush having an axial spindle for detachable engagement with the swiveled bearings 40 by an endwise movement of the spring cushioned bearing.

2. In a vacuum cleaner suction shoe, screw 45 plugs in the ends of the shoe, swiveled bearings carried by the plugs, one of the bearings having spring cushioned endwise movement, a brush having an axial spindle for detachable engagement with the swiveled bearings 50 by an endwise movement of the spring cushioned bearing and means applied to one of the bearings for rotating the brush.

GEORGE R. PAULUS.
